2 SHEETS—SHEET 2.

UNITED STATES PATENT OFFICE.

CHARLES RICKARD KJELLSTROM, OF ROCKFORD, ILLINOIS.

COMBINED FIRE-ESCAPE AND ALARM.

1,141,716.

Specification of Letters Patent.

Patented June 1, 1915.

Application filed May 18, 1914. Serial No. 839,246.

To all whom it may concern:

Be it known that I, CHARLES R. KJELLSTROM, a citizen of the United States, residing at Rockford, in the county of Winnebago and State of Illinois, have invented certain new and useful Improvements in Combined Fire-Escapes and Alarms, of which the following is a specification.

The present invention relates to a combined fire escape and alarm, and one object of the invention is to provide a fire escape, which is normally positioned so as not to obstruct the view from the windows, which in ordinary fire escapes, makes them very unsightly.

Another object is to make it operable from any floor and to lock it in a position conveniently situated with regard to all the windows in the same vertical line.

Still another object is, that it gives automatically an alarm in all the floors simultaneously as soon as a person descends on the ladder to escape fire in any one of the floors, when the ladder is swung to, or, with the ladder in normal or inoperative position, if a person attempts to run up the ladder from below.

In the accompanying drawings, is illustrated one embodiment of this invention, and, Figure 1 shows a front elevation of a part of a house wall with the fire escape in open or inoperative position. Fig. 2 is a plan view of Fig. 1. Fig. 3 is a view similar to Fig. 2 with the fire escape in operative position. Fig. 4 is a vertical section in larger scale of a portion of one of the rungs in the ladder and the side bar. Fig. 5 is a section along line 5—5 of Fig. 4. Fig. 6 is a vertical transverse section of a portion of the center post of the ladder showing an electric contact. Fig. 7 is a section along line 7—7 of Fig. 6. Fig. 8 is a plan view of a supporting bracket with latch, partly in section. Fig. 9 is a side view of the bracket on a portion of the main post.

In a bottom bracket 20 preferably provided with ball bearings, is mounted to turn, the main post 21, which I prefer to make tubular. The main post is kept in upright position by other bearing-brackets 22, secured by bolts on the face of the house wall. The top bracket 23 may form a closing cap for the upper end of the main post 21. Arms 24 extend sidewise at certain intervals from the main post 21, being fixedly secured thereon and provided each with a

fixed handle, conveniently situated to be reached by a person in the room. The handle has a downward extension 26 which is suitably shaped to engage with a spring-latch 27, projecting through the side of each bearing bracket 22, and hold the ladder rigid in its operative position slightly away from the window, as shown in Fig. 3, the latch being best illustrated in Figs. 8 and 9.

On the back of each arm 24 is provided a heel 28 which abuts against the face of the bracket 22, when the ladder stands in its normally open position, as indicated in Fig. 2. The outer end of each of the arms 24 has a cylindrical bearing portion 29 which fits closely around the central post 30 of the ladder. As shown, this central post is also tubular. Through the cylindrical portion 29 of each arm runs a rung 31 horizontally. The rungs, as here shown, are made of gas pipe and corresponding cuts are made for them in the center post in order to key the parts together. If found necessary, the intermediate rungs may be similarly secured in brackets fitting snugly on the center post 30. The ends of the rungs are connected by side bars 33 and T's 34.

As will be seen from the plan views, Figs. 2 and 3, the ladder stands parallel to the wall, when in inoperative position, and slightly at an angle when in use, and the arms 24 are bent in horizontal direction, so as to leave the side bars free in order to have no obstructions for a person's hands. At least one, 35, of the rungs is given a slight vertical play in its bearings, having its ends supported on springs 36. Suitably insulated contacts 37 and 38 are provided on the under side of the rung 35 at its middle and the corresponding bearing portion 29. The contacts are in the circuit 40 of a battery 39 and connected with an alarm 41 on each floor. A latch, preferably in the shape of a bent spring 43 is mounted near the middle of the rung 35, so as to lock it in contacting position directly it has been depressed. A releasing member 44 extends outward so that on pulling on the member 44, the rung will be raised by the springs 36. Directly the rung 35 is pressed down by anyone descending or ascending the ladder, all the alarms 41 will consequently start going.

At the bottom of the ladder is shown a short ladder 42, which is hung so that it may be folded upward between the main ladder and the wall, when the fire escape is not in

use. This is done to make the fire escape less accessible from the ground except when in use, when the extension portion 42 falls down by its own weight while the fire escape 5 is being swung into position.

In Fig. 1 is shown an attachment for facilitating the hoisting of the fire hose to the upper floors. Suspended from the uppermost one of the arms 24 is a tackle with pulleys 45 and rope or chain 46, which is long enough to be reached from the ground or from the bottom of the ladder.

The operation and use of the device is evident from the above description, and 15 needs no further explanation.

What I claim as new is:—

1. In a fire escape including a ladder having a movable rung, opposing electric contacts on said rung and said ladder respectively, for closing an electric circuit, said contacts being inserted in said circuit whereby the circuit will be closed on the moving of the rung. 20

2. In a fire escape including a ladder having a movable rung, opposing electric contacts on said rung and said ladder respectively, bearings in the ladder for said rung, said bearings having longitudinal slots allowing slight vertical movement of said 30 rung, said contacts being inserted in a circuit whereby the circuit will be closed on the moving of the rung.

3. In a fire escape including a ladder having a movable rung, opposing electric contacts on said rung and said ladder respectively, bearings in the ladder for said rung, said bearings having longitudinal slots allowing slight vertical movement of said rung, and springs normally holding the rung 35 in its uppermost position, said contacts being inserted in a circuit whereby the circuit will be closed on the moving of the rung.

4. In a fire escape including a ladder having a movable rung, opposing contacts on said rung and said ladder respectively, bearings in the ladder for said rung, said bearings having longitudinal slots allowing slight vertical movement of said rung, springs normally holding the rung in its 45 uppermost position, a locking member retaining the rung in its lowermost position, said contacts being inserted in a circuit whereby the circuit will be closed on the moving of the rung.

5. In a fire escape including a ladder having a movable rung, opposing contacts on said rung and said ladder respectively, for closing an electric circuit, said contacts being inserted in said circuit whereby the circuit will be closed on the moving of the rung, a central post from which the ladder is suspended, a hinge-device for swinging the ladder horizontally from inoperative to 60 operative position, and means for securing the ladder in the latter position.

6. In a fire escape comprising a ladder having a movable rung, opposing contacts on said rung and said ladder respectively, for closing an electric circuit, said contacts being inserted in said circuit whereby the 70 circuit will be closed on the moving of the rung, a central post from which the ladder is suspended, a hinge-device for swinging the ladder horizontally from inoperative to operative position, means for securing the 75 ladder in the latter position, said hinge device having a main post, bearings for the main post permitting the turning of the ladder from one extreme position to another, and means for thus turning the ladder. 80

7. In a fire escape including a ladder having a movable rung, opposing contacts on said rung and said ladder respectively, for closing an electric circuit, said contacts being inserted in said circuit whereby the circuit will be closed on the moving of the rung, a central post from which the ladder is suspended, a hinge-device for swinging the ladder horizontally from inoperative to operative position, means for securing the 90 ladder in the latter position, said hinge-device having a main post, bearings for the main post permitting the turning of the ladder from one extreme position to another, and sidewise extending arms from said main 95 post, said central post being carried by said arms.

8. In a fire escape including a ladder having a movable rung, opposing contacts on said rung and said ladder respectively, for closing an electric circuit, said contacts being inserted in said circuit whereby the circuit will be closed on the moving of the rung, a central post from which the ladder is suspended, a hinge-device for swinging the ladder horizontally from inoperative to operative position, means for securing the ladder in the latter position at a slightly oblique angle relative to the house wall, and abutment members on said hinge-device limiting the turning of the ladder in one direction so as to hold it parallel to the house wall. 100

9. In a fire escape including a ladder having a movable rung, opposing contacts on said rung and said ladder respectively, for closing an electric circuit, said contacts being inserted in said circuit whereby the circuit will be closed on the moving of the rung, a central post from which the ladder is suspended, a hinge-device for swinging the ladder horizontally from inoperative to operative position, means for securing the ladder in the latter position, said securing means comprising a spring-actuated plunger 115 and a member constructed to engage with said plunger situated in the movable and stationary parts of the hinge-device respectively. 120

10. In a fire escape including a ladder 130

- having a movable rung, opposing contacts on said rung and said ladder respectively, for closing an electric circuit, said contacts being inserted in said circuit whereby the 5 circuit will be closed on the moving of the rung, a central post from which the ladder is suspended, a hinge-device for swinging the ladder horizontally from inoperative to operative position, means for securing the 10 ladder in the latter position, said hinge-device having a main post, bearings for the main post permitting the turning of the ladder from one extreme position to another, and sidewise extending arms from said main 15 post, said central post being carried by said arms, said turning means comprising a handle on one of said arms, said handle forming a stop for the turning of the ladder when in its operative position.
- 20 11. In a fire escape including a ladder having a movable rung, opposing contacts on said rung and said ladder respectively, for closing an electric circuit, said contacts being inserted in said circuit whereby the 25 circuit will be closed on the moving of the rung, a central post from which the ladder is suspended, a hinge-device for swinging the ladder horizontally from inoperative to operative position, and means for securing 30 the ladder in the latter position.
12. In a fire escape, including a ladder having a movable rung, opposing contacts on said rung and said ladder respectively, for closing an electric circuit, said contacts 35 being inserted in said circuit whereby the circuit will be closed on the moving of the rung, a central post from which the ladder is suspended, a hinge-device for swinging the ladder horizontally, said central post 40 being carried by said hinge-device.
13. In a fire escape including a ladder having a movable rung, opposing electric
- contacts on said rung and said ladder respectively, bearings in the ladder for said rung, means for holding the rung out of 45 contact and means to lock said rung in contacting position.
14. In a fire escape including a ladder having a movable rung, opposing electric contacts on said rung and said ladder respectively, bearings in the ladder for said rung, means for holding the rung out of contact and means to lock said rung in contacting position, and means for releasing 50 said locking means.
15. In a fire escape including a ladder having a movable rung, opposing electric contacts on said rung and said ladder respectively, for closing an electric circuit, said contacts being inserted in said circuit 55 whereby the circuit will be closed on the moving of the rung independent of what position the ladder may have, a central post from which the ladder is suspended, a hinge-device for swinging the ladder horizontally between two extreme positions.
16. In a fire escape including a ladder having a movable rung, opposing electric contacts on said rung and said ladder respectively, for closing an electric circuit, 60 said contacts being inserted in said circuit whereby the circuit will be closed on the moving of the rung, a central post from which the ladder is suspended, a hinge-device for swinging the ladder horizontally 65 from a position flat against the wall to a position in front of a window.

In testimony whereof I affix my signature in presence of two witnesses.
